(No Model.)

P. N. BARDO & T. FORD.
HYDRANT.

No. 430,262.

Patented June 17, 1890.

UNITED STATES PATENT OFFICE.

PETER N. BARDO AND THOMAS FORD, OF NEWPORT, KENTUCKY, ASSIGNORS
TO THE BOURBON COPPER AND BRASS WORKS, OF CINCINNATI, OHIO.

HYDRANT.

SPECIFICATION forming part of Letters Patent No. 430,262, dated June 17, 1890.

Application filed July 18, 1889. Serial No. 317,865. (No model.)

To all whom it may concern:

Be it known that we, PETER N. BARDO and THOMAS FORD, citizens of the United States, residing at Newport, in the county of Campbell and State of Kentucky, have jointly invented certain new and useful Improvements in Hydrants, of which the following is a full, clear, and exact description, reference being had to the accompanying drawings, forming part of this specification.

Our invention relates to that class of hydrants generally known as "fire-plugs" or "street-washers," and has for its object the improvement in the construction and efficiency of operation of this class of hydrants. It is, moreover, an improvement upon Patent No. 365,896, issued to us July 5, 1887.

The novelty of our invention will be hereinafter set forth, and specifically pointed out in the claim.

In the accompanying drawings, Figure 1 is a longitudinal section in elevation of a hydrant containing our invention and with the valve closed. Fig. 2 is an enlarged plan view 25 of the valve-seat and arch. Fig. 3 is an enlarged plan view of the waste-valve.

The same letters of reference are used to indicate identical parts in all the figures.

With the exceptions to be pointed out, the 30 construction may be substantially that of the patent above referred to, and it is only necessary here to state that A is the cap, B the body, C the waste-chamber, D the valve chamber or shoe, E the frost-jacket, F the nozzle, 35 G the valve-rod, H the valve, I the upper guide for the valve-rod, and J the sand-guard.

Screwed into the lower end of the waste-chamber C is the valve-seat for the valve H, consisting of a ring K, with its inner lower 40 edge beveled and its outer lower edge flanged, as shown at a, Fig. 2. Extending up from the ring K, and preferably integral with it, is an arch M, with a perforation b through its top cross-piece for the passage of the valve-rod G, which fits snugly therein, and is guided thereby at its lower end. Secured upon the rod G, beneath the cross-piece of the arch, and preferably by a set-screw c, so as to render it adjustable, is the waste-valve L, whose 45 outer surface is recessed to receive a rubber

or leather packing that bears against the inner side of the upright d of the arch. When the valve H is opened, the valve L is lowered and closes the waste-vent e, which is a tube inserted through the upright d and waste-chamber C, just above the ring K, and when the valve H is closed the valve L is raised to uncover the vent e and permit the escape of the water within the body of the hydrant and the waste-chamber.

In the construction of the hydrant shown in our former patent the valve-chamber was made cylindrical, and was fitted within the lower end of the waste-chamber, and the waste-valve was made circular and fitted 55 within the valve-chamber; but as the sediment in the water would settle between the walls of the two chambers the removal of the valve-chamber was apt to be rendered difficult, or even impossible; hence we have 60 omitted the wall of the valve-chamber entirely, and only left the ring K, which can be removed very easily, as it never is affected by the deposit of sediment owing to the screw-threads; but when the walls of the valve-chamber were omitted there was no support 65 or guide to keep the lower end of the valve-rod in the center of the ring in order to properly guide to two valves. To obviate this difficulty resort was had to the arch M, having an opening b for the passage of the valve-rod G. The omission of the wall also removed the vent e, except it be located in one of the uprights of the arch, which afforded 70 a smooth vertical surface against which the waste-valve could be moved without catching upon any sharp edges or corners, as would happen if the vent were placed in the ring at any other point than in line with one of the uprights. By placing the vent near 75 the lower end of one of the uprights and centering the valve-rod by the arch the necessity of a circular form of waste-valve was avoided, and only a segment or portion of a circle was required to contain the packing and move it 80 over and away from the vent. Besides reducing the weight and cost of the valve by this construction, the friction was also reduced from that of a large circular band to 85 only a mere fraction of it, and by arranging 90 the lower end of one of the uprights and centering the valve-rod by the arch the necessity of a circular form of waste-valve was avoided, and only a segment or portion of a circle was required to contain the packing and move it 95 over and away from the vent. Besides reducing the weight and cost of the valve by this construction, the friction was also reduced from that of a large circular band to 100 only a mere fraction of it, and by arranging

the valve in a vertical line with the arch any lateral pressure upon the valve-rod by the valve is taken up by the entire arch and a very secure support is obtained.

5 Still another advantage secured by placing the waste-vent above the ring, instead of within it, is that the flow of water is not checked to so great an extent as it would be if the valve came entirely down into the ring, 10 and it also permits of a wider waste-valve being used, which can be so arranged that when the main valve is seated the lower edge of the waste-valve is just above the vent. In this position the waste-vent is closed as soon 15 as the main valve moves downward the distance of the diameter of the vent, which can be made very small, and it remains closed until the main valve returns to that point in closing, thus reducing the waste, while the 20 main valve is open to the minimum, which is an important consideration in large cities, and especially during hot dry weather, when considerable water is being used. It also permits of the hydrant being used with less 25 than a full head without letting water escape at the vent all the time, which could not be done if the vent were placed within the ring, and by making the valve segmental instead of circular the obstruction to the flow of the 30 water through the hydrant is reduced to the very lowest point, which, with the other advantages, makes it a very efficient device in every respect.

Another change from the construction 35 shown in our former patent consists in leaving a space between the outer surface of the upright and the inner surface of the wall of the waste-chamber to avoid the possibility of the uprights from engaging with any sediment which might be within the waste-cham-

ber, and thus interfering with the free rotation of the ring and the arch in their removal; but this change necessitated the use of a tube for the vent, as in the former construction the two walls were so close together that the 45 holes through them were virtually continuous, but with a space between them, as shown in the present construction, the hole through the waste-chamber could not be closed by the waste-valve. With a tube inserted within the holes, however, a continuous passage from the interior of the valve-chamber to the outside of the waste-chamber is formed, and the valve will close it in the same manner as was done heretofore. 50

Having thus fully described our invention, 55 we claim—

In a hydrant, the combination, with a waste-chamber having a hole or waste-vent near its lower end, of a valve-ring in its lower end 60 having an arch projecting up into the chamber, the outer faces of the uprights of which arch are at a distance from the inner face of the wall of the waste-chamber, and one of the uprights being also provided with a hole or 65 waste-vent near its lower end above the ring, a tube removably secured within the said holes leading from the interior of the arch to the exterior of the waste-chamber, a non-rotatable valve-rod through the arch having a 70 main valve on its lower end, and a segmental waste-valve on the rod within the arch, the outer face of which is vertically movable against the inner face of the upright having the waste-vent, substantially as described.

PETER N. BARDO.
THOMAS FORD.
